UNITED STATES PATENT OFFICE.

ELMER A. SPERRY, OF BROOKLYN, NEW YORK.

METHOD OF OPERATING ELECTRODES FOR SEARCHLIGHTS.

1,357,827.

Specification of Letters Patent.

Patented Nov. 2, 1920.

Application filed December 22, 1915. Serial No. 68,116.

To all whom it may concern:
Be it known that I, ELMER A. SPERRY, a citizen of the United States, residing at Brooklyn borough, New York city, in the 5 county of Kings and State of New York, have invented certain new and useful Improvements in Methods of Operating Electrodes for Searchlights, of which the following is a specification.

10 Until the last few years, the standard source of light for searchlights has been the pure carbon arc. While the so called flaming arc lights have been developed for other uses and will give a greater candle 15 power than the pure carbon arc, they have been found to be unsuited for projector work as they possess less intrinsic brilliancy than pure carbon. It was thought, as carbon possessed the highest volatilization point of 20 any known substance, that the positive crater of a pure carbon arc possessed the highest attainable intrinsic brilliancy. This hypothesis was borne out by the results attained with flaming arcs, in which the crater 25 brilliancy was invariably lowered by the presence of the flaming materials. It was further observed that the flame possessed a much lower intrinsic brilliancy than a pure carbon crater.
30 In my U. S. Patent No. 1,227,210, granted May 22, 1917, for method of operating flaming arc lights for projectors, I have disclosed an improved method of operating flaming arc lights whereby an intrinsic brilliancy far in excess of that obtained by pure carbon or by an ordinary flaming arc light 35 is obtained. This invention relates to certain improvements thereof whereby the forming of a deep crater in the positive electrode which is very essential to the successful production of my arc is rendered more certain. In order to understand clearly the 40 advance in the art which this invention represents, I have shown in the drawings a representation of a few of the steps made 45 in the development of the invention.

Referring to the drawings, Figures 1, 2 and 3, illustrate the conditions under which I first observed the superluminescent flame 50 which is the distinguishing feature of my invention, Figs. 1 and 2 showing the different appearances of the flame, and Fig. 3 the appearance of the arc after this flame has disappeared. Fig. 4 is an elevation of my 55 arc showing the preferred burning conditions, with the two electrodes shown in sec-

tion. Fig. 5 is a diagram showing a curve plotted with reference to the voltage drop in the different portions of the arc flames. Figs. 6, 7, and 8 illustrate the influence of 60 the total current flowing on the velocity of the negative flame. Figs. 9, 10, and 11 illustrate the influence of current density on the positive flame. Fig. 12 shows the arc operating at a lower amperage but with higher 65 current density than in the preferred form shown in Fig. 4. Fig. 13 is an elevation of one of the positive carbons after burning, showing the slight taper and the graphite ring formed thereon. Fig. 14 is a view of 70 Fig. 15 is a front view of my preferred form of arc.

While studying the possibility of employing the white flaming arc for projector 75 work, I discovered an entirely new and paradoxical result. Very high grade, homogeneous, white flaming, solid, positive electrodes were employed in which the flame materials were baked in the carbons. The ordinary 80 appearance of a flaming arc light is shown in Fig. 3. The carbon consumption is very slow and the positive 1 forms a blunt rounded tip 2. The luminous flame 3 extends across the entire arc length from positive 1 85 to negative 4. There is furthermore no observable separation or division between the positive and negative flames. But I observed, while running the arc at from 30 to 40 amperes, a sudden and remarkable increase in the brilliancy of a portion 5 of the 90 flame and at the same time the arc flame (Fig. 1) appeared to separate into two parts or flames 6 and 7 one of which issued from each electrode. The flames were not entirely 95 distinct, however, as spectrum analysis showed that the flaming arc materials which were contained only in the positive, permeated both flames.

The brilliant portion 5 of the flame appeared to issue from the positive crater. The most baffling discovery was that the intrinsic brilliancy of this portion of the positive flame was much greater than that of pure carbon. Upon a further increase in the 100 current the arc assumed more the appearance shown in Fig. 2. Neither arc was permanent, however, but would always break down after running a short time and revert to the usual form of flaming arc shown in Fig. 3. I 105 conceived the idea that if this super brilliant flame could be rendered stable and properly

controlled or confined, that a source of light would be produced which would be much superior to the pure carbon arc.

Briefly stated, a source of light should 5 fulfil the following requirements in order to be suitable for projector work:

1. The source of light should be of small dimensions; as on this depends the concentration or angle of dispersion of the beam.

10 2. The light should have a constant position, since any change in position such as the flickering of the flame is greatly augmented in the searchlight beam.

15 3. The light should be symmetrical, either spherical or disk shaped, as the shape of the beam and the sharpness of the edge of the beam depend on this point.

20 4. The source should have the maximum intrinsic brilliancy or candle-power per unit area since the intensity of the beam is dependent directly thereon.

5. As little shadow should be cast on the mirror as possible.

25 After many experiments I developed a form of flaming arc light which makes use of the super-intensive flame, mentioned above, to its best advantage. Upon further increase of the amperage and current density, I found that the super-intensive flame 30 became more steady and the line of demarcation between the two flames became gradually more sharp. Above 130 to 140 amperes the two flames (Figs. 4, 12 and 14) became entirely distinct, and the brilliancy 35 of the positive flame became more pronounced. Spectrum analysis of these flames showed that no interchange of elements took place between the flames, so that none of the negative flame reached the positive and vice 40 versa. The two conditions under which the arc operated most successfully were high amperage (about 150 amperes) coupled with high current density in the positive electrodes (about 500 amperes per sq. in.). Under 45 these conditions an arc of exceptional length (from $\frac{7}{8}$ in. to 1 in.) was formed.

The appearance of my preferred form of arc is shown roughly in Fig. 4. Upon considering the requirements for a projector 50 light and comparing them with the qualities of this light, it will be found that this arc meets every requirement. A minimum shadow is cast by the negative, since it is far removed from the positive carbon, the 55 shadow decreasing rapidly with the distance. By far the greater portion of the light is emitted from that portion 8, of the positive flame confined within and to the immediate vicinity of a crater 9 which I 60 cause to be formed by a method hereinafter described. This flame is allowed to escape, if at all, only at the top of the crater. This flame vapor is produced much more rapidly than the vapor from the negative carbon.

65 It seems to consist of a homogeneous mass

of incandescent vapor, and is not divisible into separate parts or zones. Its brilliancy may vary through wide limits depending on whether it is properly controlled by the negative flame as shown in Fig. 4 by means 70 pointed out hereinafter, or whether it is allowed to escape as shown in Fig. 14. An interesting fact concerning this flame is that when the crater becomes about 8 or 9 mm. in depth the bottom seems to be more or less 75 concealed by the apparently opaque brightness of the flame (Fig. 15). This may indicate that the entire brilliancy or emissivity issues from the flame, and that but a small portion of the total light issues from the 80 carbon itself. This, of course, is in sharp contrast to the present type of searchlights in which practically the entire light issues from the surface or tip of the positive electrode. 85

The negative flame 9, it will be noted, seems to comprise several zones or parts. The inner zone (a) which is hereinafter referred to as the tongue, is a very high velocity stream at the very center of the negative flame. It is the most luminous part of the flame and appears of a yellowish color. Zone (b) surrounds this tongue and is also of higher velocity than the outer portions of the flame but has very little luminosity. 95 Zone (c) is a very thin sheath surrounding this nonluminous zone, is of a purple color, and seems to be only a bright inner lining for zone (d). The latter zone comprises the main body of the negative flame and is the 100 color and brilliancy of the ordinary arc flame between carbon electrodes. It should be noted that it is this zone which is made use of as an impinging force against the positive flame to properly control it as hereinafter explained. Zone (e) is the outer mantle of a ruddy color which is present in 105 all arcs and is probably due mainly to the combustion of the outer portions with the air. Although the negative flame consists of 110 the above mentioned zones, it always behaves as a unit so that while it is possible to control the direction of the entire flame one part can not be controlled irrespective of the other parts. 115

The positive electrode 1', itself preferably consists of an outer shell 13 of pure carbon and an inner core 14 which contains especially prepared but well known white flaming arc materials. These materials 120 may comprise cerium or other rare earth fluorids or the like, which should be uniformly baked in the carbon. The materials used, however, not only serve to increase the luminosity of the flame, but are 125 made so as to aid in the formation of the crater 9 mentioned above. The formation of this crater is one of the most important portions of my invention, and positive means are therefore taken to insure its be- 130

ing formed and being maintained, as I make use of the crater as a container for the flame as above explained. Furthermore, the crater causes practically all of the light 5 to issue within the zone of the mirror, so that all of the light is made use of in the searchlight beam. The action of the special admixture of materials in the core in the formation of the deep crater may be explained as follows: The anode drop from the highly refractory, though pure, carbon shell to the arc is much higher than the corresponding drop from the special impregnated core to the arc. It therefore follows 10 that when the arc is struck there is a strong tendency of the core to burn back or recede to a depth sufficient to equalize the voltages in the two cases. That is, the anode drop from the core plus the drop through the 15 flame within the crater approaches in equality, the anode drop from the pure carbon shell. But, even with carbons of the above characteristics, a crater will not form under the conditions present in the ordinary white 20 flaming arc. This is caused by the rapid burning away of the perimeter of the carbon shell which is in all probability due primarily to contact with the air or with the negative flame. This difficulty is automatically overcome in my lamp by striking 25 a balance between the refractory qualities of the shell and the current density employed to burn the positive carbon away with just sufficient rapidity so that only a 30 predetermined, but important spindling takes place. This spindling of the carbon is so regulated under these conditions, that it will not be sufficient to interfere with the crater, on the one hand, while on the other 35 it possesses the important advantage that a smaller light source is thereby produced.

In order to illustrate further this action in the formation of the crater, I will point out at this point, the electrical characteristics that I observe with this form of arc light. By exploring with slender carbon rods within the two arc flames, and noting the voltage drop that took place in the different positions, I was enabled to plot the 45 curve shown in Fig. 5.

The curve is laid out with units of arc length for abscissæ and volts for ordinates. From this it will be noted that the cathode drop is in the neighborhood of 9 volts and 50 the drop through the negative flame approximately 15 volts, and that the total drop of the positive flame and anode is in the neighborhood of 47 volts. The cathode drop, it will be noted, is the same as in 55 the pure carbon arc, while the anode and positive flame drops could not be measured separately, as the exploring rods could not be inserted within the crater without extinguishing or distorting the arc. I did 60 65 not deem it necessary to determine directly

this value, as the anode drop for ordinary white flaming arcs is known and results obtained indicate that the anode drop of the special core remains about the same as for the ordinary flaming arc, *i. e.*, about 13 70 volts, this being very much less than the 36 or 37 volt drop for pure carbon. It will thus be seen that one of the important results of the special impregnated core is to secure this greatly reduced anode drop, for 75 reasons which will presently appear.

Let us now consider the most striking feature of the curve, viz., the tremendous drop in voltage that takes place in the short positive flame which is largely, if not wholly, 80 confined within the crater. This shows that an enormous amount of energy is expended within and adjacent the crater and, when the current density is also taken into account, the energy density proves to be 3.6 85 times as high as the energy density of the pure carbon positive crater. A rough calculation of the energy consumed in this flame will show that something like five to ten kilowatts are consumed within the short 90 length of the positive flame which as is shown in the diagram seldom exceeds 15 mm. This tremendous concentration of energy consumption doubtless explains easily 95 the super-luminosity of the positive flame. 100 The presence of the aforesaid special mixture of flaming arc materials not only has the effect of reducing the anode drop as stated and of adding luminosity to the flame, but also performs an additional important function of at least increasing in effect the specific resistance of the positive flame under the conditions stated as is evidenced by the large voltage drop therein. 105 So that although the difference between the anode drops of pure carbon and the impregnated core is, roughly speaking, 22 to 27 volts, the flame does not have to be a long one nor does the crater have to be dug very deep to produce a sufficient column of luminescent vapor to cause this additional 110 22 to 27 volt drop between the bottom and mouth of the crater, due as stated, to the specific resistance of this vapor column being very high. It is not essential to this discussion 115 that we should understand the true scientific nature of this resistance. Whether it is due to electro-chemical action or whether it is physical or simply resistance is as yet problematical.

Proper burning conditions are also very important. Thus, as stated above, the positive flame should not be allowed to escape from the crater, but should be closely confined. If allowed to escape at all it should be directed from the crater in a certain definite direction preferably upwardly at the top of the crater. This will confine the burning portion of the shell to a comparatively small portion of the rim or lip. The proper 120 125 130

control of the positive flame is best effected by means of the negative flame 9. When employing high currents it is always found that the negative flame possesses considerable velocity. This phenomenon seems to be practically independent of the size of the negative electrode, and hence it is entirely independent of current density and seems to depend solely upon the total current flowing. 5 A very small negative is preferable, however, so that the minimum shadow may be cast on the projecting mirror thereby. As illustrating the effect of total current flowing on the velocity and pressure of the negative flame, attention is called to Figs. 6, 7 and 8 which show how with a gradual increase in amperes flowing the negative flame will gradually push the positive flame back nearer the positive electrode. The currents 10 used in these tests were 7, 15 and 25 amperes in Figs. 6, 7 and 8 respectively.

In order to cause the negative flame to perform practically and yield the best results I have found that it should be given 15 a positive directive force since otherwise the direction of the flame is apt to vary and the steadiness of the arc be adversely effected. To illustrate the importance of this feature, especially for a large and therefore an unobstructed arc, I may state that 20 I found this arc to be inherently unsteady even to an extent which will cause it to lose the greater portion of its brilliancy unless a well defined steadyng force is given to 25 the negative flame or blast which will prevent any deflecting pressure such as upward air currents from changing or altering this direction.

For instance, if a solid negative carbon 3' 30 is employed, the requisite arc length maintained and no other extraneous means are provided for directing the negative flame, the positive and negative flames 9' and 8' tend to ride up on each other as shown in 35 Fig. 14, making a high arch 10, and the voltage across the arc increases to such an extent that the arc is very unsteady and most easily extinguished. Also it is to be noted that the negative flame does not issue 40 steadily from the tip, but shows a tendency to issue from the top as shown at 25.

I have tried various directive influences 45 upon the negative arc flame. The preferred form may be stated as follows: I have discovered that a small core 10', preferably more rapidly burning than the shell and containing arc sustaining materials, can be made to give just the desired directive influence to the negative flame to prevent the 50 above mentioned trouble when maintaining the proper arc length. Such a core also confines the flame to the tip 11 of the negative electrode, which burns almost invariably concave or into a small crater 12. In 55 addition to the core, I prefer to provide a

copper coating 32, on the negative to increase its conducting capacity. In order to use this directive negative blast so that it may confine the positive flame to the best advantage, I find it necessary to cause a 70 definite impinging contact between the two flames across the crater mouth in such a manner as to utilize the broad zone *d* of the negative flame so that it entirely covers the mouth of the positive crater and thereby 75 serves to impinge the whole body of positive vapor, not allowing it to issue at either side. It is also important that a steady and somewhat upwardly inclined current be created at the contact of the two flames. 80 This sort of impingement may be such that it still allows a steady, but not too free, escape of some of the spent positive luminous vapor in a constant direction and thus prevents flaring and flickering of the arc 85 which results when the flame from the positive crater is allowed to escape in any undetermined direction, as it is necessary that it remain under perfect control by the negative flame. This sidewise impingement of 90 the negative with the positive flame may be best secured by positioning the negative electrode at an angle to the positive electrode as shown in Fig. 4, but I make no claim to this angular positioning, *per se*, 95 since all sorts of angles have heretofore been used and proposed in this art.

I am aware that attempts have been made to increase the steadiness of the arc by using 100 negative electrodes with a core of more refractory material than the shell so that the negative will burn to a slender point. It will be noticed that I prefer to employ carbons having just the reverse burning characteristics, inasmuch as the core is more 105 rapidly burning than the shell, invariably producing a definite concavity or crater 12 at the tip of the negative, which persistently aids in imparting a definite directive force 110 to the negative flame. Another important effect of the negative core is to aid in maintaining a long arc, the advantages of which were above pointed out.

The velocity and pressure of the positive 115 flame is also of great importance, since this flame should on the one hand not be strong enough to push into or through the negative flame and on the other hand it should be strong enough to push its way out at least to the mouth of the crater so as to secure the 120 important function of light saturation above pointed out with regard to this flame so that it may obscure to the proper extent the lower light intensity of the crater surface lying behind it. After many experiments, I determined that the velocity of the positive 125 flame was a function of the current density, illustrating how the positive flame can be made to even push its way through the high velocity stream of the negative flame. It 130

therefore appears that I have discovered a simple and dependable method of controlling the relative velocity of the two flames, and hence the depth of the positive, namely 5 by varying the total current flowing and the current density in the positive electrode.

Another portion of my invention that is dependent upon these factors is the appearance of the superluminescent positive flame, 10 upon which the success of this invention is dependent. As above pointed out this phenomenon which I have termed the high intensity effect seems to be dependent to some extent on the total current flowing. But the 15 current density at the tip of the positive electrode also plays an important part. Thus in the preferred form shown in Fig. 4, a current of 150 amperes is being used with a positive electrode of 16 mm. diameter. If 20 the same electrode is retained and the current reduced, the high intensity effect will almost entirely disappear at about 100 amperes, but if the size of the electrode 1' is reduced, the high intensity effect will appear 25 in permanent form at much lower currents. Fig. 12 shows the appearance of the arc employing 90 amperes with a positive electrode 30 of 11 mm. diameter. The arc will also possess a similar appearance with 80 amperes and an electrode of 8.5 mm. It should 35 be noted however, that in order to retain this effect as the current is decreased, that the current density must be increased, so that a point is soon reached where the resistance of the positive electrode becomes a 40 serious drawback. It also appears probable that the high intensity effect cannot be made to appear when the total current flowing falls below a certain minimum, no matter 45 what current density is employed.

The above tests were made with carbons which were shielded from oxidation closely behind the tip by a highly refractory sleeve. Similar results may be obtained however, 45 without a shield, if larger carbons are used to maintain the cross section at the crater of the same diameter, since spindling will take place for a considerable distance back of the tip, if the carbon is exposed to the air. 50 In order to maintain the depth and symmetry of the crater I also find it desirable

to rotate the positive carbon continuously which condition is represented by the arrow 20. The rotation has a double advantage. It primarily causes the deep crater to be permanent and symmetrical by preventing the burning away of the upper lip. But, furthermore, when the arc is operating as shown in Figs. 4 and 12, the emitted or exhausted vapor from the arc and a portion of the negative flame licks the outer rim of the positive crater as it turns and deposits on the outside of this rim a continuous graphite ring 23 which performs the extremely useful function of protecting the 65 positive carbon from excessive tapering at the outer edge of the crater or electrode tip, which, being the hottest portion of the positive electrode, exposed to the air, is the part for which protection is most necessary. 70 Under some operating conditions, this graphite ring is found to build out beyond the shell as shown in Fig. 12 at 31 where it adds very materially in the formation and 75 maintenance of the crater.

Having described my invention, what I claim and desire to secure by Letters Patent is:

1. The method of securing a deep symmetrical crater of a positive flaming arc electrode for obtaining the high intensity effect which consists in employing a positive flaming arc electrode having a carbonaceous shell and a core, the latter containing a salt of cerium or other rare earth uniformly baked therein and having a lower anode drop than the shell, impressing a high current density on said electrode and rotating the same whereby the positive flame is substantially restricted to the crater so produced. 80

2. The method of securing a deep symmetrical crater as claimed in claim 1 in which the carbonaceous negative electrode employed has a carbonaceous core containing 85 arc supporting material.

In testimony whereof I have affixed my signature in the presence of two witnesses.

ELMER A. SPERRY.
